ATTORNEY

UNITED STATES PATENT OFFICE.

HERMANN ESSER, OF HOBOKEN, NEW JERSEY.

DESIGN FOR A BOTTLE.

SPECIFICATION forming part of Design No. 28,024, dated December 14, 1897.

Application filed August 31, 1897. Serial No. 650,200. Term of patent 14 years.

To all whom it may concern:

Be it known that I, HERMANN ESSER, a citizen of the United States, residing at Hoboken, in the county of Hudson and State of New Jersey, have invented a certain new and original Design for a Bottle; and I do hereby declare the following to be a full, clear, and exact description of the same, reference being had to the accompanying drawings, forming a part hereof.

Figure 1 is a top elevation of a bottle embodying my design. Fig. 2 is a vertical section of the same on the plane of the line 2 2 in Fig. 1, and Fig. 3 is a perspective view of the same.

The essential features of my design are as follows:

A is the body of the bottle, which consists

of a bottom, top, and sides and is provided with corners $a\ a'\ a''\ a'''$.

N is the neck, which springs upward from the top surface of the bottle and is in the usual form of a tube or prism. It is placed oblique to the vertical axis of the bottle and its axis prolonged intersects the lower corner of the bottle diagonally opposite.

What I claim as new is—

The design for a bottle substantially as shown and described.

In testimony whereof I have hereunto set my hand the 30th day of August, 1897.

HERMANN ESSER.

Witnesses:

J. FINCK,
A. W. HERBER.
